UNITED STATES PATENT OFFICE.

ANDREW McLEOD, OF ARCH HILL, NEAR AUCKLAND, NEW ZEALAND.

BRANDING APPARATUS.

SPECIFICATION forming part of Letters Patent No. 789,052, dated May 2, 1905.

Application filed January 18, 1904. Serial No. 189,592.

To all whom it may concern:

Be it known that I, ANDREW McLEOD, engineer, a subject of His Majesty the King of the United Kingdom of Great Britain and Ireland, and a resident of Arch Hill, near the city of Auckland, in the Provincial District of Auckland and Colony of New Zealand, have invented certain new and useful Improvements in Branding Apparatus, of which the following is a specification.

This invention relates to branding apparatus which may be advantageously employed for branding cattle, horses, and other animals, as well as inanimate things and objects.

It mainly consists of a pipe forming a reservoir, with a pump and feed-valve at one end, a stop cock or tap at the other end, and another pipe fitted within the reservoir reaching downward from the stop-cock, a continuation-pipe screwed into the reservoir-pipe or stop-cock, having its outside threaded to allow a nut to be screwed up or down thereon, also a plate carrying springs, a ball inwardly screw-threaded, and another plate fitted around said ball and to tops of said springs to screw up and down as required. The last plate carries a circular upright flange, to which a perforated hood or cowl is secured, to the outer end of which the brand-plate is secured.

On the accompanying drawings five figures are shown, of which—

Figure 1 is an elevation of the upper part of the invention, showing the top portion of the reservoir-pipe, the stop cock or tap, the continuation-pipe, plates, springs, ball, cowl or hood, and brand-plate. Fig. 2 is a sectional view of the parts shown in Fig. 1, except the stop-cock and reservoir-pipe. Fig. 3 is a perspective view of the brand-plate. Fig. 4 is an elevation of the reservoir-pipe broken, showing the pump, feed-valve, inner pipe, stop-cock, and part of lower end of continuation-pipe; and Fig. 5 is a sectional view of the parts shown in Fig. 4.

The reservoir-pipe A has a pump B fitted into its lower end and a feed-valve C provided in its side near the lower end, as shown in Figs. 4 and 5, though the feed-valve C may be provided in the end beside the pump B. The stop cock or tap D, which may be of any suit-

able construction and is used for the purpose of cutting off the supply of fluid from the burner, is screwed onto the upper end of the reservoir-pipe A and over the lower end of the continuation-pipe E. The inner pipe F is carried the full length within the reservoir-pipe A, though it may be made shorter, if thought advisable, and is connected to the lower end of the continuation-pipe E at G.

The continuation-pipe E is outwardly screw-threaded, as shown in Figs. 1, 2, 4, and 5, so that the lower plate H, centrally bored and threaded, and the inwardly and centrally screw-threaded ball J may be screwed up or down, as it may be required. Springs K are suitably fitted to and between the lower plate H and the upper plate L, which upper plate L fits around the ball J. A flange M projects upwardly from the upper plate L, to which a hood or cowl N is secured by screw-bolts and nuts O, though the connection may be made in any other suitable way. A brand-plate P is adjustably secured to the upper end of the hood or cowl N, as shown in Figs. 1 and 2, and perforations or small openings T are made in the hood or cowl N, as shown. The continuation-pipe E is carried through the lower plate H and ball J and into the hood or cowl N and has its upper end R so made that the burner and heater or a primus or other suitable burner V may be screwed thereonto, so as to allow the inflammable matter or gas issuing from the said upper end R of the continuation-pipe E to be forced therefrom into a nose or spreader placed on the said burner, whereby such intense fire heat can be produced that the brand-plate P will be kept continuously heated at, if so desired or required, a white heat or at a lesser heat. A fine gauze screen (not shown on the drawings) can be fitted within the continuation-pipe E near its upper end and a wick reaching therefrom down to the said cock or tap D, so as to filter the inflammable matter passing therethrough. The flange M is made in two parts, the upper one being screwed to the lower one, so as to fit better round the ball J.

Uis an inwardly-opening check-valve mounted on the upper end of the pump B.

To put this brand into use, the reservoir-

pipe A is filled through the feed-valve with the necessary inflammable matter or heat-making agent, which is pumped up and passed into the burner connected to the end R of the pipe E and 5 on being projected from the burner is lighted in the ordinary way by match or such like, when such a heat is produced that the brand-plate P, as before stated, becomes intensely hot, and it can be applied to whatever is to be 10 branded, whether animate or inanimate, with the result that an immediate impression is obtained which is clean and well cut and with animals saves a great deal of the suffering which the beast has now to endure. The heat 15 being continuous, the brand-plate is always ready for use and can be applied at any time and at the most opportune moment, and, moreover, it can be readily carried from place to place, and as its fire is self-contained an auxiliary portable fire and fire-raising plant are 20 dispensed with, whereby considerable time is saved and disappointment from the ordinary irons cooling is avoided.

The springs, the lower plate, and the stop 25 cock or tap may be dispensed with, so that smaller makes of brands may be made handier and more portable when constructed without these parts and be sufficiently effective, as with them (the smaller brands) the adjustable action is not so necessary.

Having fully described my invention, what I desire to claim and secure by Letters Patent is—

1. A branding device having a reservoir, a 35 continuation-pipe communicating with the reservoir, two plates mounted on said pipe, one of the plates being positively adjustable and yieldable devices secured to and between

said plates, the one end of each of said devices being adjustably connected to the adjustable 40 plate.

2. A reservoir for gaseous fluid, a pipe communicating with said reservoir, a burner arranged to receive the fluid through said pipe, a ball carried by the pipe, a plate supported 45 by the ball, a second plate carried by said pipe, and yieldable means mounted between the plates.

3. A reservoir for gaseous fluid, a pipe communicating with said reservoir, a ball carried 50 by said pipe, a plate supported by the ball, a second plate carried by said pipe, yieldable means mounted between the plates, a burner in operative relation with said pipe, and a branding-iron connected with said first plate. 55

4. A reservoir for gaseous fluid, a pipe communicating with said reservoir, a ball carried by said pipe, a plate supported by the ball, a second plate carried by said pipe, yieldable means mounted between the plates, a burner, 60 a branding-iron, and a cowl surrounding the burner and connected with the branding-iron and first-mentioned plate.

5. A branding device having a reservoir provided with a feed-valve, a pump associated 65 with and adapted to receive fluid from the reservoir, a continuation-pipe arranged to receive the fluid from said reservoir, a valve to control the flow of fluid from the reservoir to the continuation-pipe, and a burner associated 70 with said continuation-pipe, having tilting and longitudinal movements relative thereto.

ANDREW MCLEOD.
